CLAIM

The ornamental design for a syringe plunger, as shown & described.

DESCRIPTION

FIG. 1 is a perspective view of a syringe plunger showing my new design;

FIG. 2 is a right side elevation view thereof, the left side elevation view being identical;

FIG. 3 is a top plan view thereof, the bottom plan view being identical;

FIG. 4 is rear elevation view thereof; and,

FIG. 5 is a front elevation view thereof.

FIG. 6 is a perspective view of another embodiment of the syringe plunger;

FIG. 7 is a right side elevation view thereof, the left side elevation view being identical;

FIG. 8 is a top plan view thereof, the bottom plan view being identical;

FIG. 9 is rear elevation view thereof; and,

FIG. 10 is a front elevation view thereof.

The features shown in broken lines depict environmental structure only and form no part of the claimed design.
